(57) **CLAIM**

The ornamental design for a pet waste bag holder, as shown and described.

DESCRIPTION

FIG. 1 is a top front perspective view of the present invention pet waste bag holder;

FIG. 2 is a front elevational view of the invention;

FIG. 3 is a rear elevational view of the invention;

FIG. 4 is a top plan view of the invention;

FIG. 5 is a bottom plan view of the invention;

FIG. 6 is a left side elevational view of the invention; and,

FIG. 7 is a right side elevational view of the invention.
